PATENTED APR. 26, 1904.

No. 758,344.

H. WITTE.
WINDOW SHADE RETAINING DEVICE.
APPLICATION FILED SEPT. 14, 1903.

NO MODEL.

FIG. I.

FIG. II.

Attest:-

M. Smith
E. S. Knight

Inventor:-
Hubert Witte:
By Knight, 1904.

UNITED STATES PATENT OFFICE.

HUBERT WITTE, OF ST. LOUIS, MISSOURI, ASSIGNOR TO ST. LOUIS CAR COMPANY, OF ST. LOUIS, MISSOURI.

WINDOW-SHADE-RETAINING DEVICE.

SPECIFICATION forming part of Letters Patent No. 758,344, dated April 26, 1904.

Application filed September 14, 1903. Serial No. 173,080. (No model.)

To all whom it may concern:

Be it known that I, HUBERT WITTE, a citizen of the United States, residing in the city of St. Louis, State of Missouri, have invented 5 certain new and useful Improvements in Window-Shade-Retaining Devices, of which the following is a full, clear, and exact description, reference being had to the accompanying drawings, forming part of this specification.

10 My invention relates to a retaining device for holding car-window shades in any position into which they may be moved.

The invention consists in features of novelty hereinafter fully described, and pointed out in 15 the claims.

Figure I is a front elevation of a shade applied to a window and containing my retaining device. Fig. II is a vertical section of my retaining device with parts broken out. Fig. 20 III is an end view of the curtain-retaining device. Fig. IV is a partial section taken on line IV IV, Fig. II. Fig. V is a view illustrating a modification of the means for operating the retaining-device rods.

25 A designates the frame of a window in which are the usual grooves B. (See Figs. II and IV.)

C is a window-shade in which my improved device is shown.

30 1 designates a sleeve seated in the lower end of the window-shade and extended transversely through a pocket therein. In this sleeve is a longitudinal slot 2.

35 3 is a face-plate secured to the sleeve 1 at the location of the slot 2 by a screw 4. The face-plate 3 contains slots 5, that register with the slot 2 in the sleeve 1.

6 designates a pair of pull-fingers that are arranged to operate in the sleeve 1 and which 40 project through the slots 2 and 5 to permit of their being grasped by a person's fingers to move them toward each other.

7 designates pull-rods each having its inner end seated in the pull-fingers 6 within the 45 sleeve 1 and extending through said sleeve and beyond its terminations. Seated in each end of the sleeve 1 are two armed bearing-bars 8. These bearing-bars have bushing portions 9, which enter the sleeve and are provided at

their ends with pairs of lips 10. The pull-rods 7 extend loosely through the bushing portions 9 of the bearing-bars 8.

11 designates leaf-springs secured intermediate of their ends to the outer ends of the pull-rods 7. The ends of these leaf-springs 55 bear against the bearing-bars 8 between the lips 10, as seen in Figs. II and III.

12 designates shoes carried by the pull-rods 7 and resting against the outer faces of the leaf-springs 11.

In the practical use of my retaining device the leaf-springs 11 exert a constant pressure against the bearing-bars 8, and they ride in the window-frame grooves B to hold the shoes 60 12 at their outer faces against the window-frame at the bases of the grooves therein. In this manner frictional engagement between the device and the window-frame is secured and the shade is held at any point to which it may be moved. When the shade is to be 70 raised or lowered, the pull-fingers 6 are drawn toward each other to create a pull upon the pull-rods 7, and the leaf-springs 11 are thereby moved toward the bearing-bars 8, while their ends remain in bearing with said bars 75 and the friction-shoes 12 are removed from engagement with the window-frame, so that the shade may be moved. Immediately upon the pull-fingers being released the leaf-springs return the shoes to the window-frames to 80 again hold the shade.

In Fig. V, I have shown a modification of the means for moving the pull-rods of my device. In this modification each pull-rod 7^a bears at its inner end a rack 7^b. 6^a is a pinion that meshes with the teeth of both of the pull-rod racks and which when rotated serves 85 to impart movement in contrary directions to the pull-rods with the same intent as that where the pull-fingers 6 are used.

I claim as my invention—

1. In a shade-retaining device, the combination of a sleeve, bearing-bars at the ends of said sleeve, leaf-springs to bear against said bearing-bars, and pull-rods for compressing 95 said leaf-springs, substantially as set forth.

2. In a shade-retaining device, the combination of a sleeve, bearing-bars at the ends of

said sleeve, leaf-springs to bear against said bearing-bars, pull-rods for compressing said leaf-springs, and friction-shoes carried by said leaf-springs, substantially as set forth.

5 3. In a shade-retaining device, the combination of a sleeve, bearing-bars fitted to the ends of said sleeve and having diverging arms, lips carried by said bearing-bar arms, pull-rods operated in said sleeve, leaf-springs con-

nected to said pull-rods and having their free ends seated between the lips of said bearing-bars, and friction-shoes at the outer faces of said leaf-springs, substantially as set forth.

HUBERT WITTE.

In presence of—

A. DIEKMANN,
M. H. MURPHY.
